MULTIPLANE X-RAY APPARATUS

Oswald C. Hollstein, Secaucus, N. J., assignor to
F-R Machine Works, a firm

Application February 5, 1949, Serial No. 74,753

18 Claims. (Cl. 250—53)

1

This invention is directed to novel X-ray apparatus and parts thereof. In one of its more specific aspects the invention is directed to novel apparatus for multiplane fluoroscopy and parts thereof.

It is well known that fluoroscopy has become practically indispensable in fracture work and also in the bronchoscopic clinic. In about 1935 Dr. W. Edward Chamberlain proposed a multiplane fluoroscopic apparatus shown on page 391 of "Radiology," volume 34, No. 4 (1942) and later proposed driving its fluoroscopic crescent shaped staging about the center inside of the crescent. While that apparatus was very useful, it was not entirely satisfactory because of the following disadvantages inherent therein: (a) rotation of the fluoroscopic crescent staging about the vertical axis of the vertical support moves the fluoroscopic screen horizontally and away from the area under examination and consequently a readjustment is necessary after each of such rotations, (b) the control for rotating the crescent side-wise was located behind the crescent and consequently, effecting any such movement required the operator to leave his normal viewing position and go to the rear of the crescent to actuate the control to attain this side-wise movement, (c) the operator, standing in the normal position in front of the crescent, usually could not move the entire unit along the ceiling tracks without disturbing the adjustment unless he first went to the rear of the crescent and locked the crescent to the support to prevent rotation about the vertical axis. It was proposed by said Dr. Chamberlain to employ a motor to drive the entire assembly to effect linear motion of the assembly along the ceiling tracks.

The present invention was made to provide multiplane X-ray apparatus in which the aforesaid disadvantages in the main were eliminated and to provide other advantages. This was accomplished by the novel combination of parts exemplified in the illustrative embodiment herein described and shown in the accompanying drawings, wherein:

Fig. 1 is a side view of an embodiment of my invention.

Fig. 2 is an enlarged front view of a part of the apparatus shown in Fig. 1, with a portion being cut away.

Fig. 3 is an enlarged side view, with a part cut away, of the embodiment shown in Fig. 1.

Fig. 4 is a top plan view of a set of shutters and part of its operating mechanism.

2

Fig. 5 is a view similar to Fig. 4 of another pair of shutters.

Fig. 6 is a wiring diagram of the motor drive circuit.

Fig. 7 is a diagrammatic view of the drum switch part of Fig. 6, and shows the switch turned to down position so that the crescent may be turned clockwise.

Fig. 8 is a view similar to Fig. 7, with the drum switch turned to the up position so that the crescent may be turned counter-clockwise.

As shown in the drawings, the illustrative embodiment of the invention is supported from the ceiling by a pair of horizontally disposed tracks

10 mounted for transverse movement on a pair of tracks 9 fixedly secured to the ceiling and located close thereto. The novel apparatus may be moved horizontally in one direction along said tracks 10 on wheels 11, and also in a direction at 90° to said first direction on wheels 8 running on tracks 9. Connected to said wheels 11 and depending vertically below the tracks 10 is a vertically disposed telescopic support 12 having an outer member or tubing 13 and an inner member or column support 14, movable up into and downwardly out of the tubing 13. A counterweight (not shown) may be located in tubing 13 and connected to the upper end of the column 14 of the telescopic support 12 to counter-balance the downward force exerted upon the column 14 by the weight of the column 14 itself and by the weight of the elements supported thereby and hereinafter described.

A goose neck support 15 is secured to the lower end of the vertically adjustable column 14 for pivotal movement about the longitudinal axis of column 14 as the center. The goose neck support 15 may be swung to any desired angular position over an arc of 360°, and may be latched in the desired angular position by a latch band

40 16 associated with the goose neck 15 and the column 14. A downwardly extending hollow support or housing 17 is pivotally secured to and depends from the vertically disposed leg of the goose neck 15 by a pivot-pin 18 extending through the housing and into said leg at about the mid-length thereof. The pivotal supporting pin or axis 18 is horizontally disposed at approximately right angles to the column 14. The lower extremity of the vertical leg of the goose neck 15 is forked, and located in said fork is a nut 19 pivotally connected to the tines thereof.

Pivotally mounted in the housing 17 is a ball bearing support 20 carrying a threaded shaft 50 21 making threaded engagement with the nut

55 21

19 and having one end thereof extending through the housing 17, with a crank-handle 22 tied to that end of the shaft 21. The crank-handle 22 is located below and approximately in line with the exposed end of the goose neck 15 so that it is within reach of the operator when standing in normal position at the front of the apparatus. By turning the crank-handle 22 either clockwise or counterclockwise, the support 17 together with the elements supported thereby may be swung about the pivot or axis 18 as much as 30° to either side of the vertical. The swinging about axis 18 and latching in any desired angular location is accomplished by rotation of the crank-handle 22 to rotate the shaft 21 acting through nut 19 to cause rotation about the pivot 18.

The housing 17 is open at the lower part thereof, and mounted in said housing are a plurality of pairs of roller bearings or supporting guide rolls 25 spaced from each other. Located in the housing 17 is an electric motor 26 having a worm 27 keyed to its motor drive shaft and meshing with a driven gear 28, which together with a larger spur gear 29 is keyed to a shaft carried by the housing 17.

An arcuate support or crescent 30 is supported by the housing 17 and has an arcuate rail guide 31 extending outwardly from each side thereof, and located between the pairs of rollers 25 which guide the crescent 30 during its rotation about its center or imaginary or virtual horizontal axis A. Secured to the backside of the vertically disposed crescent 30 is a gear rack 32 meshing with the spur gear 29.

The crescent 30 may be a hollow closed member in the nature of a housing having a housing 33 at the lower end thereof and extending outwardly therefrom for supporting an X-ray tube 31. The lower end of the crescent 30 is enlarged, and mounted therein are lead shutter plates 35, 36, 37 and 38 for limiting the size and controlling the shape of the X-ray field on a fluoroscopic screen 40. The shutter plates 35 and 36 are slideably mounted on support bar 41 and are guided by a channel support 42. A pair of shutter plate control cables 43 and 44 are connected respectively at their lower ends to the shutters 35 and 36. The shutter plate 35 is connected directly to the cable 43 through a rod 45 anchored to the lower end of the cable 43 and to shutter plate 35. The shutter plate 36 is connected to the cable 44 through a rod 46 having one end thereof connected to cable 44 and its other end pivotally connected to one end of a link 47 pivotally mounted on a stationary post 48, and a link 49 having one end pivotally connected to the shutter plate 36 and its other end pivotally connected to the other end of the link 47.

A stationary shaft 50 is mounted in the upper end of the crescent 30, and has pivotally mounted thereon four independently actuatable bell crank-levers 51, each having respectively inner arms 53 and outer arms 54 with the latter extending outwardly forwardly towards the mouth side of the crescent 30. The upper ends of the cables 43 and 44 are respectively connected to the inner arms 53 of separate bell-cranks 51, so that the shutter plates are independently adjustable towards and away from one another.

The other pair of lead shutter plates 37 and 38 are disposed at right angles to the plates 35 and 36 and are also slideably mounted on a support rod 57 and are guided by a channel support.

58. One end of shutter cable 60 is pivotally con-

nected to one corner of a triangular link plate 61 whose opposite corner has a slot 62 and is mounted at its apex in a stationary pivot post 63. The slot 62 engages a pin 64. Pin 64 is mounted to shutter plate 37. The shutter plate 38 has an identical linkage connection 66 except that it is connected in a left hand manner and is connected to cable 68. These other ends of these shutter cables 60 and 68 are also connected to separate bell cranks 51. With this arrangement, it is possible for the operator to adjust each of the four shutter plates independently and with dispatch, because each lead shutter plate has its own control lever near the fluoroscopic screen. This arrangement permits coning of the X-ray beam down to any one of the four corners of the screen. With the conventional design the X-rays can be coned down only to areas whose centers coincide with the center of the fluoroscopic screen. Coning down to one corner permits fluoroscopy in close corners, as for example, when fluoroscopy the femoral neck. In this case the fluoroscopic screen and the shutters can be adjusted to any desired shape without being limited to a field around the center of the fluoroscopic screen. Also, when used in the bronchoscopic field, the bottom edge of the screen frame can touch the table top alongside of the patient and the fluoroscopic screen sizes can be freely adjusted without the inherent limitations of a conventional shutter. The four control levers 51 may be arranged in pairs, with one pair controlling the longitudinal and the other pair the transverse adjustment of shutters. At those times where it is found desirable to operate the shutters in the conventional manner, each pair of controls 51 may be gripped by the operator and actuated as a unit.

An open frame 70 is secured to the upper end of the crescent 30. Mounted on the frame 70 through a pivot rod 71 at the forward end thereof is the fluoroscopic screen 40. The space in the frame 70 is provided to permit the insertion of an X-ray film cassette 73 and grid 74 to allow the taking of radiographic records during operation.

A spring assembly 75 is mounted in the housing 17 and a stretch of the spring tape 76 passes under a guide roller 77 out through the housing 17 along the side of gear track 32 and is anchored to the crescent near the lower part thereof in bearing 78. The spring 75 constantly acts upon the crescent 30 and tends to rotate it counter clockwise about its center which is approximately coincident with the vertical axis of the column 14, which also is the axis of rotation of the goose-neck 15.

While the force exerted by spring 75 on the crescent 30 is insufficient in itself to cause rotation of the crescent 30, it serves to aid the motor 26 in driving the crescent 30 in that it prevents too fast a rotation of the crescent 30 in a clockwise direction and acts to speed the rotation of crescent 30 in a counter-clockwise direction. 65 When the motor is energized to drive the crescent 30 clockwise, the worm 27 acting through the gear 28 drives the spur gear 29, which in turn acting on the rack 32 drives the crescent 30. In this operation the spring 75 acts in conjunction with the motor 26 to drive the crescent 30. When the motor is energized to drive the crescent 30 in a clockwise direction, the motor drive acts against the force exerted by the spring 75.

Mounted in the crescent 30 at the upper end thereof and near the frame 70 is a drum switch

80 having a rotatable handle 81 which is located just behind and adjacent to the fluoroscopic screen 40 when the screen is in operative position. The drum switch 80 has contacts 82, 83, 84, 85 and 86. Conductor 87 has one end thereof connected to a terminal or junction plate 88 mounted in the lower part of the crescent 30 and its other end connected to a fuse 89, all being located in the crescent 30. The other end of the fuse 89 is connected to a conductor 90 which is also connected to the contact 82. Also connected to the contact 82 is one end of a conductor 91, whose other end is connected to one terminal of a normally closed limit switch 92 including a lever 93 having a roller 94 at one end thereof.

A conductor 95 has one end thereof connected to the other terminal of the switch 92 and its other end connected to one end of a variable resistance 96, whose other end is connected to a variable resistance 98 connected to the contact 83 through a conductor 99. Shunted across the variable resistance 98 is a mercury switch 101 disposed vertically in crescent 30 and being in closed position when the crescent support is in the position shown in Fig. 3. A conductor 102, which together with the conductor 87, constitutes the motor supply line and is connected to a variable resistance 103, which is connected to the contact 86. A conductor 104 is connected to the conductor 102 and to a terminal of a normally open switch 105. Another conductor 106 is connected to the contact 86 and to the other terminal of the switch 105.

When the switch 105 is open the resistance 103 is in the motor circuit as hereinafter described, however, when the switch 105 is closed the resistor 103 is out of that circuit, thus providing a means for controlling the speed of the motor 26. The switch 105 is also mounted in the crescent 30 near the frame 70, and extending therefrom and located adjacent to the actuator 81 is a finger trigger 97 for actuating the switch 105. A conductor 108 is connected to one end of the field winding 107 of the motor 26 and has a pair of contact fingers 109 and 110 connected thereto. Connected to the other end of the winding 107 is a conductor 112 having a pair of contact fingers 114 and 115 connected thereto. A conductor 116 is connected to the armature 117 of the motor and also to the contact 84. Conductor 119 is connected to the armature 117 and to a contact finger 120.

A conductor 121 has one end thereof connected to the contact 84 and its other end connected to a normally closed limit switch 122 located in the lower part of the crescent 30 and including a lever 129 having a roller at the end thereof. A conductor 123 is connected to the other terminal of said limit switch 122 and also to a variable resistance 124, which in turn is connected to the contact 85 by a conductor 126. Shunted across the variable resistance 124 is a mercury switch 128 disposed horizontally in crescent 30 and being in open position when the crescent 30 is in a position as shown in Fig. 3.

The cable 130 carries conductors 87 and 102, which terminate in a plug (not shown), which may be inserted in a female plug in the ceiling and generally carry 110 or 220 volts. Also carried by the cable 130 are additional conductors for remotely controlling the X-ray generator with push-buttons near the fluoroscopic screen.

A pair of cables 131 are high tension cables for energizing for the X-ray tube 34 mounted to

housing 33. Another cable 132 carries the conductors from the drum switch to the motor 26. All of these cables extend along the outside of the crescent 30.

5 The operation is as follows:

With the embodiment of the invention depending from the ceiling as shown in Fig. 1, a patient is placed on a table (not shown) whose top normally extends in the space between the frame 70 and the lower part of the crescent 30. The assembly may be moved up or down in the outer tubular part 13 of the telescopic member 12 at any time to adjust the vertical position thereof. With the crescent 30 disposed in the full line position shown in Fig. 1, it is possible for the operator, who normally stands in front of the open end of the crescent, to look down upon the fluoroscopic screen 40, because the supporting housing 17 together with the crescent are off-set with respect to the column 14 by virtue of the goose-neck 15. When it is desired to rotate the crescent in a counter-clockwise direction, the operator may, without changing his position, reach up over the screen 40 and turn the handle 81 to actuate the "dead man" controlled drum switch so that the connections are changed from those shown in Fig. 6 to those shown in Fig. 8; and this position is maintained as long as the operator manually holds the actuating handle 81 in that new position. The motor is thus energized to drive the worm 27, spur gear 29 which in turn drives the crescent by its action upon the gear rack 32. While this condition is maintained the crescent moves quite slowly in a counter clockwise direction due to the resistance 103 being in the motor circuit.

If it is desired to speed up the drive of the crescent, the operator, while still maintaining the handle 81 in new position, moves one of his fingers over to the upper part of the trigger finger 97 and rocks it and maintains it in rocked position in order to close and maintain closed the normally open switch 105, whereby the resistance 103 is cut out of the motor circuit. Then as the crescent approaches the desired position, the operator removes his finger from the trigger 97 while maintaining the actuator 81 in new position, and the crescent again resumes its slower speed. When the crescent reaches the approximate desired position the operator lets go of the actuator 81, which automatically turns to move the drum switch to the open position shown in Fig. 6.

To rotate the screen in a clockwise direction 55 the same procedure as before is followed, except that the actuator 81 is turned in the opposite direction to provide the connections shown in Fig. 7. If for some reason the operator neglects to remove his hand from the actuator 81 and the crescent reaches its limit to travel in either direction, then the normally closed switches 92 or 122 are actuated by the housing 17 which strikes an element thereof to open them.

The travel of the crescent 30 is further controlled, and in this instance automatically, by virtue of the mercury switches 101 and 128, which come into operation when the crescent approaches either limit of travel. When the crescent approaches its limit of travel in a counter-clockwise direction, the mercury in switch 101 flows to break the connection between its contacts continues thereby cutting in resistance 98 to reduce the speed of the motor 26. When the travel of the crescent 30 is in the opposite direction and it approaches its limit, the switches are

in the positions shown in Fig. 6. In the course of travel of the crescent 30 between about these extreme positions, connection is maintained by the mercury between the contacts of switches 101 and 128 and it is only after the fluoroscopic screen passes the horizontal and its vertical positions that the connection is broken in either of these switches to bring either the resistance 98 or 124 in the circuit. These variable resistors 98 or 124 may be so set that the sum of the resistance of either one of them and that of the resistor 103 may be such that the motor 26 may be rendered inoperable and, therefore, stopped and may be set to control the speed of the motor 26. The mercury switches, therefore, act as automatic vertical and horizontal stops. If it is desired that the screen go past either the horizontal or vertical position, then the trigger finger 97 may be actuated to thereby cut out the resistance 103 and the crescent will move at a slower speed to the desired or final end position, at which point the limit switch 92 or 122 will be automatically opened to prevent any further travel of the crescent 30. By providing these various controls, the crescent 30 may be rotated at variable speeds about an imaginary horizontal axis which is located close to and preferably intersected by the vertical or longitudinal axis of the column 14, which is approximately at right angles thereto.

The X-ray tube in the housing 33 is located in line with the shutter plates and the fluoroscopic screen 40, with the vertical axis of the column 14 passing approximately through the centers of said screen, shutters and target of the X-ray tube, when the screen is located in the horizontal position as shown in full lines in Fig. 1. The off-setting of the housing 17 by means of the goose-neck 15 not only permits viewing of screen 40, but serves the significant and equally important purpose of permitting the vertical axis of rotation of the crescent 30 to intersect and to be disposed at 90° to the horizontal axis of rotation of the crescent 30. This arrangement permits viewing of a particular area by passage of the X-ray beam at any angle over a vertical arc of 126° and also at any angle over a horizontal arc of 360°, the limitation being only the body acted upon.

Besides being able to rotate the crescent about its vertical axis through column 14, and about its horizontal axis, it is also possible to rotate the screen by turning the crank 22 to swing the crescent about the pivot 18.

I claim:

1. A multiplane X-ray apparatus comprising a normally depending vertical support, a crescent support for an X-ray tube and fluoroscopic screen and means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis.

2. A multiplane X-ray apparatus comprising a normally depending telescopic vertical support, a crescent support for an X-ray tube and fluoroscopic screen and means connecting said crescent support with said vertical support for rotation of said crescent about a virtual horizontal axis passing through the space within the periphery of said crescent, and for rotation about said support whose axis when extended downwardly is at

about right angles to and approximately intersects said virtual horizontal axis.

3. A multiplane X-ray apparatus comprising a normally depending vertical support, a crescent support for an X-ray tube and fluoroscopic screen and means including an approximately horizontally disposed pivot and connecting said crescent support with said vertical support for rotation of said crescent about a virtual horizontal axis passing through the space within the periphery of said crescent, for rotation about said support whose axis when extended downwardly is at about right angles to and approximately intersects said virtual horizontal axis and for rotation of said crescent about said pivot whose axis is at about right angles to the axis of said vertical support and to said virtual horizontal axis and is located above said crescent.

4. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, and means for rotating said crescent about said virtual horizontal axis, said second mentioned means supported by said first mentioned means.

5. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, and means for controlling said motor thereby to vary the speed of rotation of said crescent, said second mentioned means supported by said first mentioned means.

6. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, means for controlling said motor thereby to vary the speed of rotation of said crescent, said second mentioned means supported by said first mentioned means, and a spring connected to said crescent and normally tending to rotate said crescent in one direction and aiding said motor when said motor drives said crescent in said direction, and acting against the action of said motor when said motor drives said crescent in the opposite direction.

7. A multiplane X-ray apparatus comprising a normally depending vertical support, a crescent support for an X-ray tube and fluoroscopic screen, means connecting said crescent support with said vertical support for rotation of said crescent about

a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, and means including manually actuatable means for controlling said motor thereby to vary the speed of rotation of said crescent, said second mentioned means supported by said first mentioned means, and said manually actuatable means carried by said crescent at the screen supporting end thereof.

8. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, means for controlling said motor thereby to vary the speed of rotation of said crescent, said second mentioned means supported by said first mentioned means, and automatically operable crescent travel-limit switches for deenergizing said motor.

9. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a plurality of shutter plates carried by said crescent at the X-ray tube supporting end thereof, means extending along the arc of said crescent and connected to said shutter plates, and actuatable means connected to said second mentioned means for actuating said plates and located at the screen supporting end of said crescent support.

10. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, means including manually actuatable means for controlling said motor thereby to vary the speed of rotation of said crescent, said second mentioned means supported by said first mentioned means, and said manually actuatable means carried by said crescent at the screen supporting end thereof, a plurality of shutter plates carried by said crescent at the X-ray tube supporting end thereof, means extending along the arc of said crescent and connected to said plates and manually actuatable means connected to said last mentioned means for actuating said plates and located at the screen supporting end of said crescent.

11. A multiplane X-ray apparatus comprising a normally depending vertical support, a crescent support for an X-ray tube and fluoroscopic screen, means connecting said crescent support with said vertical support for rotation of said crescent about a virtual horizontal axis passing through the space within the periphery of said crescent, and for rotation about said support whose axis when extended downwardly is at about right angles to and approximately intersects said virtual horizontal axis, a motor for rotating said crescent about said virtual horizontal axis, said crescent including a cassette receiving and screen supporting frame at one end thereof, and means including manually actuatable means for controlling said motor thereby to vary the speed of rotation of said crescent, said second mentioned means supported by said first mentioned means, and said manually actuatable means carried by said crescent at the screen supporting end thereof, and located near one end of said frame.

12. A multiplane X-ray apparatus comprising a normally depending vertical support, goose-neck support, a crescent support for an X-ray tube and fluoroscopic screen and means connecting said crescent support with one leg of said goose-neck support for rotation of said crescent about a virtual horizontal axis passing through the space within the periphery of said crescent, said goose-neck pivotally connected to said vertical support for rotation about said vertical support whose axis when extended downwardly is at about right angles to and approximately intersects said virtual horizontal axis.

13. A multiplane X-ray apparatus comprising a normally depending telescopic vertical support, a goose-neck support, a crescent support for an X-ray tube and fluoroscopic screen, means connecting said crescent support with one leg of said goose-neck, said crescent being rotatable about a virtual horizontal axis passing through the space within the periphery of said crescent, said goose-neck being pivotally connected to said means, and said goose-neck pivotally connected to said vertical support for rotation about said vertical support whose axis when extended downwardly is at about right angles to and approximately intersects said virtual horizontal axis.

14. A multiplane X-ray apparatus comprising a normally depending vertical support, a goose-neck support and a crescent support for an X-ray tube and fluoroscopic screen, means connected to said crescent support with said goose-neck support for rotation of said crescent about a virtual horizontal axis passing through the space within the periphery of said crescent, an approximately horizontally disposed pivot connecting said means with one leg of said goose-neck, said vertical support pivotally connected to the other leg of said goose-neck, for rotation about said vertical support whose axis when extended downwardly is at about right angles to and approximately intersects said virtual horizontal axis, the axis of said pivot being at about right angles to the axis of said vertical support and to said virtual horizontal axis, being located above said crescent.

15. A multiplane X-ray apparatus comprising a normally depending vertical support, a goose-neck support and a crescent support for an X-ray tube and fluoroscopic screen, means connected to said crescent support with said goose-neck support for rotation of said crescent about a virtual horizontal axis passing through the space within

the periphery of said crescent, an approximately horizontally disposed pivot connecting said means with one leg of said goose-neck, said vertical support pivotally connected to the other leg of said goose-neck, for rotation about said vertical support whose axis when extended downwardly is at about right angles to and approximately intersects said virtual horizontal axis, the axis of said pivot being at about right angles to the axis of said vertical support and to said virtual horizontal axis, being located above said crescent, and means for swinging said first mentioned means about said pivot.

16. A multiplane X-ray apparatus comprising a normally depending support, a goose-neck support, a crescent support for an X-ray tube and fluoroscopic screen, one leg of said goose-neck being normally disposed approximately horizontally and being connected thereto for rotation in an approximately horizontal plane, means connected to said crescent support and said crescent support being rotatable about a virtual horizontal axis within the periphery thereof, an approximately horizontally disposed pivot connecting said means to the normally approximately vertically disposed leg of said goose-neck, the axis of said normally depending support being at about right angles to and when extended downwardly approximately intersects said virtual horizontal axis, the axis of said pivot being at right angles to said virtual horizontal axis and located above the crescent.

17. A multiplane X-ray apparatus comprising a normally depending support, a goose-neck support, a crescent support for an X-ray tube and fluoroscopic screen, one leg of said goose-neck being normally disposed approximately horizontally and being connected thereto for rotation in an approximately horizontal plane, means connected to said crescent support and said crescent support being rotatable about a virtual horizontal axis within the periphery thereof, an approximately horizontally disposed pivot connecting said means to the normally approximately vertically disposed leg of said goose-neck, the axis of said normally depending support being at about right angles to and when extended down-

wardly approximately intersects said virtual horizontal axis, the axis of said pivot being at right angles to said virtual horizontal axis and located above the crescent, a nut pivotally carried by said approximately vertically disposed leg of said goose-neck and an actuatable threaded shaft cooperating with said nut and said means for swinging said means about said pivot.

18. A multiplane X-ray apparatus comprising a normally depending support, a goose-neck support, a crescent support for an X-ray tube and fluoroscopic screen, one leg of said goose-neck being normally disposed approximately horizontally and being connected thereto for rotation in an approximately horizontal plane, means connected to said crescent support and said crescent support being rotatable about a virtual horizontal axis within the periphery thereof, an approximately horizontally disposed pivot connecting said means to the normally approximately vertically disposed leg of said goose-neck, the axis of said normally depending support being at about right angles to and when extended downwardly approximately intersects said virtual horizontal axis, the axis of said pivot being at right angles to said virtual horizontal axis and located above the crescent, a nut pivotally carried by said approximately vertically disposed leg of said goose-neck at a position below the vertical level of said pivot, and an actuatable threaded shaft cooperating with said nut and said means for swinging said means about said pivot.

OSWALD C. HOLLSTEIN.
